C. G. BUCHANAN,
MAGNETIC SEPARATING APPARATUS,
APPLICATION FILED JUNE 12, 1918.

1,865,965.

Patented Jan. 18, 1921.

UNITED STATES PATENT OFFICE.

CHARLES GORDON BUCHANAN, OF ROSEVILLE, NEW JERSEY.

MAGNETIC SEPARATING APPARATUS.

1,365,965.

Specification of Letters Patent. Patented Jan. 18, 1921.

Application filed June 12, 1918. Serial No. 239,516.

To all whom it may concern:

Be it known that I, CHARLES G. BUCHANAN, a citizen of the United States, residing at Roseville, in the county of Essex 5 and State of New Jersey, have invented certain new and useful improvements in Magnetic Separating Apparatus, of which the following is a specification.

This invention relates to magnetic separators and particularly to that type of separator wherein the material is carried over a rotary magnetic cylinder or pulley. The object of the invention is to make this pulley cheap in construction and assembly, 15 readily variable in length, and easily repaired. With this in view the pulley is formed to be built up of a series of duplicate sections assembled by simply slipping them together on the shaft and interlocked 20 by their interengagements into a rigid unit. Different lengths of pulley are easily made by varying the number of sections assembled and for each size in diameter only one set of standard parts have to be manufactured or carried in stock.

A further object of the invention is to arrange the magnet windings of the pulley sections to produce the same strength of magnetism so that there is attained a uniform 30 selective action on the material throughout the entire holding surface.

In the accompanying drawings,

Figure 1 is a plan view of apparatus embodying this invention;

Fig. 2 is a side elevation of the same;

Fig. 3 is a central sectional view of a magnetic pulley constructed in accordance with this invention;

Fig. 4 is a central section of the conductor 40 rings;

Fig. 5 is a view in section of certain of the pulley elements detached, and

Fig. 6 is a central sectional view of a modified form of magnetic pulley.

In the specific embodiment of the invention shown in the drawings, 1 is an endless belt traveling around the idler pulley 2 and the driving pulley 3, within which are solenoid windings producing a magnetic flux 50 at the periphery. The material, from which magnetic particles are to be separated, is fed onto the upper surface of the belt and carried thereby to the cylinder 3, which attracts the metallic or magnetic particles and 55 holds them against the belt while the rest of

the material as it passes down over the cylinder drops off and is discharged by gravity down the chute 4, the magnetic material is retained and carried on and later dropped off into chute 5 as the further movement of 60 the belt increases the gravity effect on the particles and decreases the magnetic attraction. Such apparatus is useful in separating magnetic ores from their gangue, and is particularly useful in removing bits of iron 65 such as broken drill points, pick points, and so forth from various ores to prevent excessive wear or breakage of the fine grinding machinery employed in the treatment of these minerals, also in separating tramp 70 iron from coal, used as pulverized fuel requiring very fine grinding, and for extracting scrap from bone-black, used in sugar refineries.

In the apparatus shown, the endless belt 1 75 may be of any desired length and may itself serve as a conveyer. The idler pulley 2 is adjustable to take up slack and the magnetic pulley 3 has its shaft 6 provided with driving means at 7. The other end of the 80 shaft 6 carries the conductor contact rings 8 and 9 for receiving the current from the brushes 10 of opposite terminals and the shaft is hollowed out or drilled to form a passageway 11 (see Fig. 3) for the wires 85 from these rings to carry the current to the solenoids mounted within the pulley.

The roll 3 is built up of a series of standard, interchangeable sections keyed to the shaft 6 and tightly drawn together by the 90 tie rods 15. Of these sections the solenoid spools 16 of magnetic material, preferably steel, carry the magnet coils 17, adjacent coils being oppositely wound so as to provide in effect a series of abutting magnets 95 and forcing the flux to the periphery of the pulley through the flanges of the spools. These spools are all alike and form duplicate units which may be assembled together in any desired number to give any desired 100 length of pulley corresponding for instance to the various standard widths of belt. Each spool 16 is provided with a peripheral spacer ring 18 preferably of brass or other material impermeable to magnetic flux so 105 that the latter will be forced to a path through the metal particles on the surface of the belt. These rings 18 complete the periphery of the pulley between the spool flanges and are formed to be assembled on 110

and interlock with the spools. Each spool 16 has a large flange 20 and a small flange 21 permitting the spacer ring 18 to slide over (see Fig. 5) into engagement with the large 5 flange which has a ledge 22 to receive and center it, while the other end 23 of the ring remains partially seated on the smaller flange 21.

The large flange 20 of each spool is recessed as at 24 to receive the smaller flange of the adjacent spool and abut against the corresponding ring 18 so that the latter is held snugly in place between the spool flanges. For economy and lightness each 10 ring 18 is channeled in cross-section and provided with the stiffening ribs 25 and, in order to interlock the parts against relative rotation, the rings 18 carry dowel studs 26 engaging in holes 27 in the spool flanges 20. 15 The spools and rings are easily assembled by simple axial movement (see Fig. 5) and positioned on the shaft 6 and fastened together by the tie rods 15 between the end plates 30 and 31 corresponding respectively 20 to the larger and smaller spool flanges 20 and 21. In order to prevent the material from being drawn onto the magnetized end flanges where it would accumulate in an 25 objectionable manner the belt is preferably 30 wide enough to overhang these flanges; and end rings 32 of brass or other non-magnetic material are provided for this overhang of the belt to run on.

In the construction shown in full lines 35 in Figs. 3 and 5, each coil 17 is a continuous winding in one direction and adjacent coils are wound in opposite directions so that the magnetic flux is forced outward not only at the ends, but also passes through the spool 40 flanges to the periphery of the pulley at a plurality of intermediate sections forming a series of gaps along the periphery. In this form it is best to have an even number of gaps, otherwise there would be what is 45 termed a "bucking" coil. For instance, if a three gap pulley were made instead of a four as shown in the drawing there would be two coils having a right-hand direction and one a left-hand direction, or vice versa. 50 With an even number of coils this is fairly balanced, but the end pieces of course are weaker than the center magnets owing to the fact that there is no wire or windings on the outside. To compensate for this relative 55 weakening of the end pieces end coil 40, as indicated in dotted lines in Fig. 3, may be added on hubs of plates 30, 31 at each end of the pulley and held in place by disks 41 of non-magnetic material. These 60 coils will be wound in a direction opposite to that of the adjacent coils to increase the flux through the magnetic end pieces while the end rings 32 and disks 41 of brass will distribute the return flux through the 65 extreme end poles.

In order to make the distribution of the flux more uniform and extended and produce a construction wherein there will be an even number of coils irrespective of the number of sections, the construction shown in Fig. 6 may be resorted to. Here each of the center coils 17' is broken up into two oppositely wound sections as indicated by the arrows in said figure. Each end piece 30' and 31' carries a half coil section 37 75 adapted to increase the magnetic strength at the ends of the pulley so as to give a substantially uniform holding power throughout the periphery. The absence of magnetic material between the adjacent sections of 80 the coils also forces the magnetic flux through paths farther out from the periphery of the pulley so that a thicker layer of material on the belt will be properly magnetized. End rings 32' and disks 41' house 85 the end coil sections and are preferably of brass or other non-magnetic material so that the flux of the extreme end pole is well distributed and the material will not gather and accumulate upon the ends of the pulley. 90

The apparatus of this invention is simple to manufacture and low in cost. Each different width of pulley is built up by assembling the required number of duplicate sections which are cheaply produced in quantity, reduce the number of different parts that have to be kept in stock, and permit the pulley to be quickly taken apart and repaired. Each section is rigidly fastened to the other and keyed to the shaft so that 100 there can be no relative slippage. While maintaining these structural advantages ample space is provided for the solenoid windings permitting a larger number of ampere turns and a larger quantity of wire 105 with a corresponding low amperage so that there will be insured an economy of current, a minimum degree of temperature in the wire, and long life to the coils.

It is obvious that various modifications 110 may be made without departing from the principle of the invention which is not confined to the specific embodiments shown or described, but is intended to cover such modifications thereof as fall within the scope 115 of the appended claims.

Having thus described my invention, I declare that what I claim as new and desire to secure by Letters Patent, is:—

1. A magnetic pulley comprising a winding supported between flanges extending beyond the periphery of said coil, and a spacer ring bridging said flanges, said spacer ring being channeled in section with inwardly directed edges engaging said flanges and an outer surface forming the periphery of said pulley.

2. A magnetic pulley comprising a shaft, a plurality of duplicate magnetic sections adapted to be each directly and independ-

ently supported on said shaft to form the pulley, each section comprising a coil spool of magnetic material having a large flange extending to the periphery of the pulley, and a small flange adapted to engage the large flange of the next adjacent spool in assembled position.

3. A magnetic pulley comprising a shaft, a plurality of duplicate magnetic sections 10 adapted to be each directly and independently supported on said shaft to form the pulley, each section comprising a coil spool of magnetic material having a large flange extending to the periphery of the pulley, a 15 small flange adapted to engage the large flange of the next adjacent spool in assembled position, and a spacer ring intervening between successive large flanges.

4. In a magnetic pulley the combination 20 with a shaft, of a plurality of duplicate magnetic spool sections each having integral flanges at each end directly and independently supported on said shaft, each spool having a separate winding thereon 25 and rings bridging the end flanges of said spools, and having circular peripheries at the belt surface of said pulley.

5. A magnetic pulley comprising a series of coil spools, at least one of said spools

having directly adjoining coils of opposite 30 polarity thereon.

6. A magnetic pulley comprising a series of coil spools, at least one of said spools having directly adjoining coils of opposite 35 polarity thereon, and a single end coil of polarity opposite to that of the adjacent intermediate coil.

7. In a magnetic pulley, a pair of coils of opposite polarity, means at the adjacent ends of said coils providing a path of low 40 permeability to the abutting fluxes, and means at the opposite ends of said coils for completing the magnetic circuit so that the flux at the periphery of the pulley will be forced outward and evenly distributed. 45

8. In a magnetic pulley, a series of coils of alternately different polarity, means providing magnetic paths of high permeability between alternate adjacent ends of coils of opposite polarity, and means providing 50 magnetic paths of relatively low permeability between the intermediate adjacent ends of said coils, so that the abutting fluxes thereat will be spread and the flux at the periphery of the pulley will be evenly 55 distributed.

CHARLES GORDON BUCHANAN.
